UNITED STATES PATENT OFFICE

CARL A. JOERISSEN, OF WASHINGTON, DISTRICT OF COLUMBIA

TYPEWRITING MACHINE

Application filed October 26, 1929. Serial No. 402,751.

The present invention relates to improvements in typewriting machines, and consists in the novel construction and arrangement of parts that will be hereinafter fully described and pointed out.

The primary object of the invention is to provide a typewriting machine which will be relatively noiseless in operation.

In the operation of typewriting machines as commonly constructed, difficulty is experienced in simultaneously producing a plurality of copies, the impressions on each of which will be equally clear. In the forms of machines heretofore proposed, in which the type bar commonly swings about a relatively fixed pivot, or the path of the travel of the type head is the arc of a circle, the contact between the type and the platen will be affected by the number of sheets of paper interposed between them. That is, when a single sheet of paper, for example, is in the machine, the final portion of the movement of the type head into printing relation with the platen will cause the type to strike squarely against the platen, or produce a uniform impression throughout the type face. If, however, a plurality of sheets of paper are introduced, the additional thickness will cause the impression to be partly produced before the type face has come into exact vertical position and the angle at which said face contacts with the outer or intermediate sheets will be such as not to produce a clear and uniform impression on each of the sheets. To avoid this objectionable feature is one of the objects of the present improvements.

Referring to the drawings:

Figure 1 is a view in elevation of a type bar action embodying the present invention, showing the type bar at rest or in normal position.

Figure 2 is a similar view, showing the arrangement of the several parts when the type bar is in printing relation to the platen.

Figure 3 is a similar view illustrating a slightly modified form of type bar actuating means.

Figure 4 is a similar view of another modification.

Figure 5 is a view of a slightly different form of actuating means for the type bar, the bar being shown in its position of rest, or non-printing relation to the platen.

Figure 6 is a view of the construction shown in Figure 5, with the type bar in printing relation to the platen.

Figures 7 and 8 are details on an enlarged scale.

Figure 9 is an elevation of another slightly different embodiment of the invention, showing the type carrier in non-printing position.

Figure 10 is a similar view, with the type bar in approximately printing relation to the platen.

Figure 11 is a detail, on an enlarged scale.

It will be understood that in the drawings only the connections between the type carrier and the cooperating actuating member or key are shown, and several of the parts of the mechanism are illustrated more or less conventionally and diagrammatically.

Referring to the drawings, 1 designates the platen of a typewriting machine, which may be of any well known or suitable construction, and in Figures 1 to 6 inclusive, the type carrier is of the ordinary form of a bar 2, having at one end a type head 3 and supported adjacent its other end in a suitable segment-like portion of the frame 4, so that it can move in a curved path from a substantially horizontal position of rest to a substantially vertical position, in which the type thereon will be in printing relation to the platen 1.

As usual, the outer ends of the type bars are shown as supported by a rest 5, when the type bars are in normal, inactive, position.

It will be understood that the drawings illustrate but one of a series of type actions, one for each type bar, and that the frame members 4, 5, are in the form of segments or curved in the direction of their length. The connections between the type bars adjacent the ends of the segments and their actuating keys will be suitably bent and of different lengths from the type action illustrated, which is assumed to be one of those relatively near the center of the segment so that

all of the parts are in substantially the same vertical plane.

As shown, each type bar 2 is provided adjacent the type head with a slot 6, through which extends a pin on a sleeve 7, carried by an arm 8 that is pivotally mounted, as at 9, on the segment 4.

Near its other end each type bar is provided with two slots 10, 11, extending generally at approximately right angles to each other, the slot 10 being longitudinally curved, and through these slots extend relatively stationary guide rods or pins 12, 13. As the arm 8 is swung about its pivot or axis 9, the type bar 5 will be caused to travel in a curved, non-circular path to bring the type head thereon into printing relation with the platen. In this movement it will be seen, by comparing Figures 1 and 2, for example, the arm 8 will 10 travel in a circular path about the axis 9, but owing to the sliding connection between the type bar and said arm, the bar will be moved through a path which is not circular or concentric with a definite axis or substantially 15 parallel to that of the arm, and, as shown by the dotted lines in Figure 2, the portion of this path adjacent the platen 1 will be on substantially a straight, horizontal, line, so that regardless of the number of sheets of paper 20 interposed between the type head and platen, the type face will strike the platen squarely and produce a uniform impression on each of the several sheets.

The particular means shown for swinging 25 the type bar from its normal, substantially horizontal, position of rest shown in Figure 1, to substantially vertical position, or into printing relation to the platen, as shown in Figure 2, includes a normally collapsed toggle, the members 14, 15, of which are respectively pivoted to the lever arm 8, and a support 16, which is pivotally connected, as at 30 17, to the frame of the typewriting machine.

The toggle member 15 is connected by a 35 link 19 with the longer arm 20 of a two-armed lever suitably fulcrumed at 21 on the machine frame, and the shorter arm 22 of which is provided with a pin 23, shown as engaging a fork in the upper end of a swinging arm 24. The arms 24, one for each type 40 action, are all mounted on a fulcrum rod 25, and each is connected by a link 26 with a suitable key lever 27.

The lever 20, 22, is also connected by a link 45 28, with the aforesaid, pivotally mounted support for the forward end of the type bar actuating toggle.

When the key lever 27 is depressed or 50 rocked about its fulcrum, it will be seen that the lever 20, 22, will be rocked to effect an expansion of the type bar actuating toggle and the parts caused to move from the positions shown in Fig. 1 to those shown in Fig. 2.

As the members 14, 15, of the type bar 55 actuating toggle come into expanded rela-

tion, as shown in Fig. 2, the swinging movement of the type bar is slightly checked and the completion of the movement of such bar into printing relation with the platen is effected by a rocking of the pivotally mounted toggle support 16.

30 designates a universal bar, which extends beneath all of the key levers 27 of the machine, and the said bar is connected approximately midway of its length to a lever 31, which engages, and is adapted to actuate a member 32 of the carriage feed escapement devices. An auxiliary universal bar 33 is arranged in the path of the several lever arms 8, so as to be struck by said arms as the 35 associated type bar comes into approximately printing relation to the platen, said auxiliary universal bar being connected with the carriage escapement feed devices by a rod 34.

With the arrangement described and illustrated, it will be seen that movement of the carriage feed escapement devices will be initiated by depression of any one of the key levers 27, and will be completed, in one direction, by the contact of the lever arms 8 connected to the several type bars, as the bars come into printing relation to the platen.

In the embodiment of the invention illustrated in Figure 3, the toggle member 15 is provided with a slightly offset portion 15a, 95 to which the link 19a is pivotally connected, and the actuating lever has its arms 20a and 21a of substantially the same length, the link 28 being connected to a lug 21b on said lever. In this form of the invention also the lever arm 24a is arranged substantially horizontal, having a pin thereon extending into a fork in the lever arm 21a.

The embodiment illustrated in Figure 4 differs but slightly from that of the preceding figures. In this embodiment each key lever 27 is provided with an upwardly extending lug 27a, which is provided with a pin that extends into a slide in the substantially horizontal member of a bell crank lever 35, 10 the other arm of which is connected by a link 36 with an arm 37 attached to the two-armed lever 20a, 21a.

In the embodiment of the invention illustrated in Figures 5 to 8, the member 14a of 11 the type bar actuating toggle is connected directly to the type bar, and in order that the bar may travel through the curved, but non-circular, path, an eccentric is interposed in the connection between the bar and pivotally 12 mounted support for the forward end of the actuating toggle.

Specifically, this eccentric connection is shown as interposed between the toggle members 14a, 15a. The toggle member 15a is provided with an enlarged head 40, in which is rotatably mounted an eccentric 41, to which the toggle member 14a is pivotally connected. The toggle member 14a is provided with a pin 42 that extends into a slot 43 formed in 13

the eccentric 41, and as the toggle is expanded and the members 14a, 15a, thereof come into substantial alignment, the pin 42 moving in the slot 43 will effect a slight rotation 5 of the eccentric 41, thus, in effect, lengthening the toggle and causing the type bar to move through the path before referred to.

In the embodiment of the invention illustrated in said Figures 5 to 8, the manually 10 operable key 50 is not provided at the forward end of a horizontal lever, but engages an arm 51 of a bell crank, the other arm of which is connected by a link 52 with the arm 22 of the two-armed lever that effects expansion 15 of the normally collapsed toggle.

In this embodiment of the invention also, the auxiliary universal bar 33 is actuated by a portion of the type bar itself contacting with a pivotally mounted member 55 that 20 extends across said universal bar.

In the embodiment of the invention illustrated in Figures 9 and 10, the type head 3a is mounted directly on the member 14b of the actuating toggle, the other member 15b of 25 which is, as in the forms previously described, supported by the pivotally mounted member 16. A carrier link 60 having slots 61, 62, corresponding to the slots 10 and 11 of the type bar of the embodiment of the invention 30 illustrated in Figures 1 and 2, for example, connects the type carrying toggle member with the segment 4 and the toggle members are connected by an eccentric so that the type head will travel in the desired curved, 35 non-circular, path in moving from the normal substantially horizontal position of Figure 9, to the substantially vertical position or printing relation to the piston shown in Figure 10.

40 It is believed that the operation and advantages obtained by the invention will be readily understood and appreciated from the foregoing description and the drawings. It will be noted that in each of the embodiments 45 of the invention illustrated the type are caused to travel from a normal, substantially horizontal, position to printing relation with the platen through a curved, but non-circular, path.

50 That is, the type are not, as has heretofore been the common practice, caused to move about a fixed pivot, or to travel in a path which is the arc of a true circle, but the path of travel is of such form that the face of each 55 type is in a substantially vertical plane slightly before coming into exact printing relation to the platen so that whether one or a plurality of sheets of paper be interposed between the platen and type, all parts of the 60 face of the type will simultaneously contact with the ribbon by which the impression on the paper is produced. The curved, but non-circular, path of travel of each type is such that the portion thereof immediately adjacent 65 the platen is along a substantially hori-

zontal line as distinguished from the constructions heretofore proposed, in which, particularly when a plurality of sheets of paper are to be simultaneously impressed or printed upon, the plane of the type face is oblique to 70 the vertical plane including the forward end of the horizontal diameter of the platen.

The particular means for actuating the type carrier, namely, a normally collapsed toggle, the forward end of which is connected 75 to a pivotally mounted supporting member acts to cause the type to effect a printing operation with a minimum amount of noise.

There can, of course, be modification in 80 many of the details illustrated without departing from the invention, and, as before noted, the several views are more or less diagrammatic and several of the parts are shown conventionally. Except as particularly defined in the following claims, the invention 85 is not to be understood as being limited to the exact details shown.

I claim:

1. In a typewriting machine, the combination of a platen, a type bar having a type head 90 at one end and provided near its other end with two guide slots extending substantially at right angles to each other, fixed guide rods extending through said slots, a pivotally mounted arm connected with the type bar by 95 a connection permitting relative movement between the arm and bar in the direction of the length of the latter, and means for rocking said arm to carry the type bar from a substantially horizontal position to a substantially vertical position and move the type 100 head into printing relation to the platen through a curved, non-circular, path.

2. In a typewriting machine, the combination of a platen, a type bar having a type head 105 at one end and provided near its other end with two guide slots extending substantially at right angles to each other, fixed guide rods extending through said slots, a pivotally mounted arm connected with the type bar by 110 a connection permitting relative movement between the arm and bar in the direction of the length of the latter, a normally collapsed toggle for rocking said arm to carry the type bar from a substantially horizontal position 115 to a substantially vertical position and move the type head into printing relation to the platen through a curved, non-circular, path.

3. In a typewriting machine, the combination of a platen, a type carrier mounted to move in a non-circular, curved, path to and from printing relation to the platen, and means for moving the type carrier to printing position including a normally collapsed toggle and a pivotally mounted member connected to the end of the toggle remote from the type carrier, movement of the type carrier toward the platen being checked by expansion of the toggle, prior to the carriers 120 reaching printing position, and being com- 125

pleted by movement of said pivotally mounted member.

4. In a typewriting machine, the combination of a platen, a type carrier mounted to move in a curved path to and from printing relation to the platen, and means for moving the type carrier to printing position including a normally collapsed toggle, one member of which is connected to the type carrier, and a pivotally mounted member connected to the end of the toggle remote from the type carrier, the connection between the type carrier and said pivotally mounted member including an eccentric whereby the length of the toggle is increased during movement of the type carrier toward printing relation to the platen.

5. In a typewriting machine, the combination of a platen, a type carrier mounted to move in a non-circular, curved, path to and from printing relation to the platen, and means for moving the type carrier to printing position including a normally collapsed toggle, a pivotally mounted support for the end of the toggle remote from the type carrier, a lever having one arm connected to said pivotally mounted support, a link connection between said lever arm and the toggle, whereby the latter will be expanded as the lever is rocked about its fulcrum, and a manually operable key adapted to rock said lever, movement of the type carrier to printing position being checked as the toggle reaches expanded position and completed by rocking of said pivotally mounted support.

6. In a typewriting machine, the combination of a platen, a type carrier mounted to move to and from printing relation to the platen, and means for moving the type carrier to printing position including a normally collapsed toggle and a pivotally mounted member connected to the end of the toggle remote from the type carrier, the connection between the type carrier and said pivotally mounted member including an eccentric whereby the length of the toggle is increased during movement of the type carrier toward printing relation to the platen, such movement being checked as the toggle reaches its maximum expanded position and completed by a rocking of said pivotally mounted member.

7. In a typewriting machine, the combination of a platen, a type carrier mounted to move to and from printing relation to the platen, and means for moving the type carrier to printing position including a normally collapsed toggle, the members of which are connected by an eccentric joint, whereby the length of the toggle will be increased as it reaches its maximum expanded position while moving the type carrier into printing relation to the platen.

8. In a typewriting machine, the combination of a platen, a type carrier mounted to

move to and from printing relation to the platen, and means for moving the type carrier to printing position including a normally collapsed toggle, the members of which are connected by an eccentric joint, and a pivotally mounted member connected to the end of the toggle remote from the type carrier, such movement of the type carrier being checked as the toggle reaches its expanded position and completed by a rocking of said pivotally mounted member.

In testimony whereof I have hereunto set my hand.

CARL A. JOERISSEN.
